UNITED STATES PATENT OFFICE.

HARRY W. TITGEN, OF PHILADELPHIA, PENNSYLVANIA.

SAND CLEANING AND RECLAIMING UNIT.

Application filed August 7, 1926. Serial No. 127,940.

My invention relates to sand blast apparatus, having particular relation to sand cleaning and reclaiming means therefor.

One object of my invention is to provide an apparatus of the class described characterized by its compactness and simplicity of design; by its relatively low operating expense; and by its relatively high efficiency as compared with that of the rectangular screens, suction boxes and like mechanisms of the prior art.

Another object of my invention is to provide a sand cleaning unit, wherein a housing for a revolving screen is mounted on the head of an elevator casing, permitting the screen to be operated by the elevator head shaft.

Another object of my invention is to provide a two-part housing for a rotatable screen, one of the parts being provided with clean sand, dust and tailings discharge outlets, the other part constituting a removable closure for the screen.

With these and other objects and applications in mind, my invention further consists in the details of construction and operation, hereinafter described and claimed and illustrated in the accompanying drawings, wherein—

Fig. 1 is a detail, top plan view of a sand cleaning and reclaiming unit embodying my invention;

Fig. 2 is a side elevational view of the structure of Fig. 1; and

Fig. 3 is a reduced transverse sectional view of the housing for the screen taken on the line 3—3 of Fig. 2.

In the embodiment of my invention shown in the drawing, used sand is carried from the sand-blast room or other supply point (not shown) by means of an elevator 1 which is enclosed in a housing 2 having side and end walls 3 and 4, respectively. The casing 1 comprises a head portion 5 having a removable hood section 6, which may be secured in position as shown in Figs. 1 and 2, wherein a lower edge 7 is positioned to rest on horizontal shoulders 8 formed by flanges 9 and 11 of angles 12 and 13, flanges 14 and 15 of which are respectively secured to the end and side walls 4 and 3. Side walls 16 of the hood section 6 may be provided with slots 17 extending to the lower edge 7 for the removable reception of ends 18 of an elevator head shaft 19.

The shaft end portions 18 may be respectively journaled in bearings 21 which are mounted for vertical adjustment in slots 22

formed in brackets 23. The brackets 23 are respectively mounted on the horizontal flanges 11 of the side wall angles 13. The vertical adjustment of the head shaft may be effected by pairs of screw bolts 24, 25, which are threaded in the bracket 23 so as to extend into engagement with opposite portions of the bearings 21, said adjustment occurring upon the loosening of one of the bolts 24, 25 and the tightening of the other.

The used sand may be discharged from the elevator 1 through an enclosed chute 26 which leads from the casing head portion 5 downwardly through a wall 27 of a housing 28 to an upper end 29 of an axially inclined screen 31. The screen 31 is mounted on an inclined shaft 32, a lower end 33 of which extends through a wall 34 spaced from the wall 27 and is supported on a bearing 35. The latter is mounted on a horizontal flange portion 36 of an angle 37, a vertical flange 37' being secured to the end wall 34.

An upper end 38 of the inclined screen shaft 32 extends through the housing end wall 27 and is journaled in a bearing 39 carried by a horizontal flange 41 of an angle 42. Opposite ends 43 and 44 of the horizontal flange 41 are mounted on horizontal flanges 45 and 46 of angles 47 and 48 respectively. Vertical flanges 49 and 51 of these angles are respectively secured to opposite side walls 52 and 53 of the housing 28.

In accordance with my invention, the screen housing 28 is mounted on the elevator head portion 5, as shown in Figs. 1 and 2, wherein one of the side angles 47, 48, preferably the former, is extended so that the vertical flange 49 thereof may be secured to the elevator casing side wall 3. The screen housing 28 may be further supported in the position shown by means of a second angle 54, a vertical flange 55' of which is secured to the elevator casing end wall 4, a horizontal flange 55 being secured to the corresponding supporting flanges 45 and 46 of the side wall angles 47 and 48 respectively. The supporting flange 55 of the angle 54 provides a support for a bearing 56 which rotatably carries a shaft 57.

An inner end of the shaft 57 carries a beveled gear-wheel 58 which meshes with a bevel gear-wheel 59 mounted on the outer raised end 38 of the screen shaft 32. The outer end of the shaft 57 carries a sprocket wheel 61 adapted to engage a sprocket chain 62 which extends therefrom around a sprocket

wheel 63 mounted on the elevator head shaft 18 and an idler 64. The latter is mounted for vertical movement so as to compensate for such slack in the chain as may result from the adjustment of the elevator head shaft 18, the particular mounting shown comprising a bracket member 65 having a horizontal section 66 secured to the side wall angle 13 and a vertical section 67 slotted to receive a pivot pin 68 for the idler 64.

The housing for the screen 31 may comprise the upper part 69 and a lower part 73. The lower part 73 includes the spaced longitudinally extending side walls 52, 53, and end walls 74, 75, the latter respectively constituting continuations of the walls 34 and 27. The side walls 52 and 53 comprise vertical sections 76 and 77, which respectively support the angles 48 and 47, and inwardly inclined sections 78 and 79 which terminate in a horizontal bottom wall 81. The end wall 75 extends inwardly to form one wall of a clean sand hopper 82, an opposite wall 83 of which extends upwardly from the bottom wall 81 between the side walls 52 and 53 and terminates adjacent to a lower open end 84 of the screen 31. The hopper 82 is thus provided with an open upper end 85, which extends from the inlet end 29 to the outlet end 84 of the screen 31, whereby all clean sand passing through the screen 31 may be collected into one chamber. The sand may be conveyed away from the chamber 82 through an outlet 86 in the bottom wall 81 and piping 87 leading to a tank 88 of a sand blast machine.

The tailings passing from the lower end 84 of the screen 31 are deposited in a chamber 89 formed by the adjacent side and end walls of the lower housing part 73 and the inclined wall 83 which also forms one wall of the clean sand chamber 82 as just noted. An outlet pipe 91 serves to permit the withdrawal of the tailings from the chamber 89. The dust incident to the normal operation of the rotary screen may be drawn into a dust chamber 92 through a screen 93 which extends inwardly from an upper edge of the vertical side wall section 76 substantially parallel to the inclined section 78 between the inner and outer walls 75 and 83 of the sand chamber 82. The dust may be removed from the chamber 92 through a suction pipe 94 connected to an opening in the vertical wall section 76.

Since it may be desirable under some conditions to have access to the screen 31 as well as the chambers 82, 89 and 92, I have constructed the upper part 69 of the screen housing 28 in the form of a removable cover 95. The cover 95 may be of semi-cylindrical form with opposite ends 96 and 97 resting on supporting flanges 98 and 99 extending inwardly from the end walls 34 and 27, respectively. The cover may be locked in position by screws 101 which extend through flange edge por-

tions 102 and 103 to the horizontal flanges 45 and 46 of the side wall angles 47 and 48, respectively.

When the elevator is operated, used sand in the blast room is raised to a point above the chute 26 and then discharged therethrough into the open upper end 29 of the screen 31, which all the while is being operated by the head shaft 18 through the sprocket chain 62, shaft 57 and gearing 58, 59. The rotation of the screen 31 causes the separation of the sand from the scale or other undesirable materials, so that the sand readily passes through the screen to the clean sand hopper 82 from which it may be discharged through the piping 87 into the tank 88 for the sand blast machine. The tailings are discharged from the screen 31 through the open end 84 into the chamber 89 and conveyed therefrom through the outlet pipe 91. Such dust as is formed during the above reclaiming operation passes through the perforated wall 93 into the dust chamber 92 from which it passes into the suction pipe 94 returning to a dust collector or other receptacle (not shown).

While I have shown only one embodiment of my invention, for the purpose of describing the same and illustrating its principles of construction and operation, it is apparent that various changes and modifications may be made therein without departing from the spirit of my invention and I desire, therefore, that only such limitations shall be imposed thereon as are indicated in the appended claims or as are demanded by the prior art.

I claim:

1. In a sand cleaning and reclaiming unit in combination, an elevator casing, a screen, a two-part housing therefor, one part of which comprises spaced side and end walls, and angles respectively secured to said side walls so that the flanges thereof provide elongated supporting shoulders, at least one of said angles being extended to provide a supporting portion adapted to be secured to one wall of said elevator casing.

2. A sand cleaning and reclaiming unit comprising a housing, a pair of angles, the flanges of which are so secured to the housing side walls as to permit the other flanges to serve as supporting shoulders, and an elevator casing, one wall of which is rigidly secured to a flange of at least one of said angles.

3. In a sand cleaning and reclaiming unit, an elevator head having a casing provided with side and end walls, a screen in communication with said casing, a housing for said screen provided with clean sand and dust discharge outlets, and means for supporting said housing on said elevator casing comprising an angle, one flange of which is so secured to a side wall of said housing and said casing side wall that the other flange may constitute a supporting shoulder, said hous-

ing having a removable cover for said screen adapted to engage said supporting shoulder.

4. In a sand cleaning and reclaiming unit, an elevator head having a casing provided with side and end walls, a screen in communication with said casing, a housing for said screen provided with clean sand tailings and dust discharge outlets, means for supporting said housing on said elevator casing comprising an angle, one flange of which is so secured to a side wall of said housing and said casing that the other flange may constitute a supporting shoulder, said housing having a removable cover for said screen adapted to engage said supporting shoulder; a second angle having one flange secured to the end wall of said casing and the other flange

mounted on said first-mentioned angle, and a shaft for operating said screen mounted on said last-mentioned flange. 20

5. In a sand cleaning and reclaiming unit, an elevator casing, a screen, a two-part housing therefor, one part of which comprises spaced side and end walls, angles respectively secured to said side walls so that the flanges thereof provide elongated supporting shoulders, at least one of said angles being extended to provide a supporting portion adapted to be secured to one wall of said elevator casing, and a shaft for operating said screen 25 supported at least in part on the extended portion of said last-mentioned angle. 30

HARRY W. TITGEN.
